SIMEON SCHOON JACKSON, OF READVILLE, MASSACHUSETTS, ASSIGNOR TO THE STAFFORD COMPANY, OF READVILLE, MASSACHUSETTS, A CORPORATION OF NEW JERSEY.

LOOM.

1,079,914.

Specification of Letters Patent. Patented Nov. 25, 1913.

Application filed August 28, 1909. Serial No. 515,046.

To all whom it may concern:

Be it known that I, SIMEON SCHOON JACKSON, a subject of Great Britain, residing at Readville, in the county of Norfolk, State 5 of Massachusetts, have invented a certain new and useful Improvement in Looms, of which the following is a specification, reference being had therein to the accompanying drawings.

- 10 Certain looms in use at the present time are equipped with devices which include a dog that is connected to a weft-fork slide so as to be actuated when such slide is moved in consequence of breakage or failure of the 15 weft, and a transmitting member that is provided with a shoulder to be engaged by the dog and also with a lip which fixes the normal position of the dog and assists in controlling the action of the dog when the 20 latter is called into play. The movement of the transmitting member produced by engagement of the dog with the said shoulder, and advance of the dog, is for the purpose of bringing about a change in the action 25 of the loom, and has been utilized to bring about a replenishment of the working weft-supply of a loom, and the devices have been constructed and combined to effect pick-finding, that is to say, to cause the first 30 pick of the fresh weft to be laid in a reopening of the proper shed to avoid a break in the weave of the web being produced. Sometimes when the weft-thread breaks it does so outside the shuttle so as to leave a 35 trailing end which is not long enough to extend in front of the weft-fork when the shuttle is at rest in the adjacent shuttle-box. Consequently, the weft-fork is not tilted when the lay next beats up. Sometimes 40 the weft extending through a shed in the warps to the shuttle in the shuttle-box at the end of its flight is intact but is too slack to tilt the weft-fork. In either case the weft-hammer engages the tail of the 45 weft-fork and acts in usual manner to advance the weft-fork slide and the dog so as to move the latter from its normal position relative to the lip, the dog thereupon assuming its secondary position, thus beginning 50 the sequence of the pick-finding action. If, however, in the case first referred to the trailing end should catch among the warp-threads in the flight of the shuttle through the next shed, or through the suc-

ceeding shed, and become woven in, as happens occasionally, the weft would thereafter act to tilt the weft-fork in regular manner, as though the breakage had not occurred. When this occurs the operation of the devices is interrupted, and while the loom continues the weaving the dog remains in its secondary position. The result will be similar if in the other case referred to the weft laid by the succeeding pick to the weft-detecting side of the loom should tilt the weft fork. Heretofore when the operation has been thus interrupted it has been necessary to return the dog by hand to its normal starting position in order that when the next weft-failure occurs the devices may act correctly and when employed for pick-finding purposes may operate to find the proper shed.

The invention has for its object to provide means for automatically replacing the dog in its normal starting position whenever it is given a different position and is left therein, as in consequence of an interruption of the regular working of the devices with which the dog is combined, after such working has been begun, or in case of the dog being accidentally disturbed from such position.

The invention consists, essentially, in the combination with a transmitting member, 85 a dog, and a lip and a shoulder with which the dog coacts, and a weft-detector under control of which the interaction of dog, lip, and shoulder occurs, of means acting to restore the dog and lip to normal starting 90 relation in case a sequence of beats that has been begun is interrupted, or in case of accidental departure from such relation.

The mechanical devices employed in carrying the invention into effect may be varied 95 in construction and arrangement in practice.

A convenient embodiment of the invention is shown in the accompanying drawings, in which latter,—

Figure 1 is a side elevation taken at one end of the breast-beam of a loom, namely at the driving side of the loom, showing certain elements of pick-finder devices with the said embodiment of the invention combined therewith. Fig. 2 is a plan view of the parts which are shown in Fig. 1. Fig. 3 is a view similar to Fig. 1, but showing the

parts arranged for finding the pick in the case of the employment of a different number of harness-changes to the round than that for which the parts are arranged in Fig. 1. Fig. 4 is a front elevation of the dog and dog-carrier, Fig. 5 is a side elevation thereof, and Fig. 6 is a top view thereof. Fig. 7 is a side elevation of the guide-stand for the striker-pin, hereinafter described, and Fig. 8 is a rear elevation thereof.

1, Figs. 1, 2 and 3, is the side-frame at the driving-side of a loom, and 2 is the breast-beam.

3 is a shipper-handle, 4 is a rockshaft on which the shipper-handle is fixed, and 5 a rod (only a portion thereof being shown) through which the shipper-handle controls the power-shipping and brake-devices (not shown). The shipper-handle is shown in the position occupied by it while the power is applied and the loom is running.

At 11 is a tripping rockshaft through which the shipper-devices and weft-replenishing instrumentalities of the loom are tripped into action. For thus tripping the shipper-devices, the said tripping rockshaft has thereon a collar 13^a which is made fast thereto by a clamp-screw 13^b and formed with a projecting lug or shoulder 13, and the shipper-handle is formed with a projecting lug or shoulder 14 with which lug or shoulder 13 engages. By reason of such engagement, forward turning movement of the tripping rockshaft acts through the lugs or shoulders 13, 14, to operate the shipper-handle so as to cause the driving-power of the loom to be unshipped, the brake applied, and the weaving action stopped to afford opportunity for conveniently effecting replenishment.

At 12, Figs. 1 and 3, is a portion of a finger that is fixed upon the tripping rockshaft by means of its hub or sleeve 12^a, Fig. 2, and a clamping screw 12^b. This finger is operatively combined in practice with devices (not shown) for automatically replenishing the working weft-supply, so that when the tripping rockshaft and finger are turned the said devices are called into action and thereby the automatic replenishment is brought about. The particular arrangement of parts that is shown in the drawings is more especially designed for employment in a replenishing loom of the well-known type in which the movement of finger 12 operates to trip a so-called change-shaft into operation, at the same time that lug 13 trips the shipper-handle to unship the driving-power from the weaving instrumentalities and apply the brake to thereby suspend the weaving action, the change-shaft during its rotation actuating the various replenishing instrumentalities to occasion a replenishment of the working weft-supply during the suspension of the weaving action, and

finally acting to restore the shipper-handle to its former position and thereby relieving the brake-action and shipping on the driving-power to resume weaving, the change-shaft itself coming to rest. The side of the loom represented in Figs. 1, 2, and 3, being that at which the shipper-handle 3 is located, is the driving side. The magazine (not shown) containing the reserve weft-supply (filled and threaded shuttles) is in practice located at the opposite side of the loom.

The drawings show the invention applied in connection with certain of the elements of the pick-finder devices of a two weft-fork loom, such elements being those which are located at the driving side of the loom, although the invention is not necessarily restricted to employment in this particular connection, nor is it limited with respect to the employment of weft-forks as the weft-detectors.

Referring briefly to the illustrated weft-detector and pick-finder devices,—15 is the weft-fork which detects for picks to the driving side of the loom, it being mounted pivotally upon the rear end of its carrying slide 16, and the latter being supported and guided by the stand 17 fixed upon the breast-beam 2 adjacent to the said side.

18 is the actuator (weft-hammer or goose-neck) that co-operates with the said fork 15, the said actuator having the shoulder 18^a which, when the fork 15 is not tilted by weft or filling between its tines and the corresponding grid of the lay, when the lay beats up after the pick to the driving side, engages the tail 15^a of the said fork and moves the slide 16 forward in its guide-stand 17. The actuator 18 is moved at the required times to feel for the tail of the fork 15 by means of a cam (not shown) on the cam-shaft of the loom. The forward movement of the slide 16 is utilized for the actuation of the dog aforesaid, which is shown at 27. For the support of the dog and the transmission of movement thereto from the slide 16, an arm 20, Fig. 2, is mounted loosely upon a supporting rod or shaft 21 extending across the loom in line with the tripping rockshaft 11. The rearwardly-extending upper end of the arm 20 is branched, the branches being separated transversely, and in holes made transversely through the two branches a pin 23 is mounted, the said pin being fixed in place by means of a clamping screw 24. The intermediate portion of the pin passes through the eye of the forwardly-projecting portion of an eye-bolt 25 having its threaded stem screwed into the front portion of the slide 16. The said eye-bolt constitutes a longitudinally-adjustable connection between the said slide and the pin and arm. A portion of the length of the pin 23 projects at the

115
120
125
130

outer side of the arm 20, and an arm 26 is hung pivotally thereon, the said arm and the slide being thereby connected together so as to compel them to move forward and rearward in unison. The arm 26 extends forward from the pin, and carries the tripping dog 27. When the actuator (weft-hammer or gooseneck) engages the tail of the weft-fork 15 and advances the slide 16, the arm 26 and dog 27 are carried forward therewith. A contracting spiral spring 29, having its rear extremity engaged with a lateral ear 29^a on the rear of guide-stand 17 and its forward extremity engaged with a screw 29^b projecting downward from the hub-portion of the dog-carrying arm 26, aids gravity in causing the said arm and dog to tend to swing downward, and also acts with a tendency to draw the said arm 26 and the weft-fork-carrying slide 16 rearward and hold the arm 20 in contact with the front surface of the breast-beam. Through the action of the said spring the arm 26, dog 27, and slide 16 are moved rearward into their normal positions after having been advanced in the manner just described. The acting portion of the dog 27 extends transversely outward above the upper end of an arm 28 rising from the hub or sleeve 12^a which is fixed, as aforesaid, upon the tripping rockshaft 11. The shoulder 28^a which the dog 27 is designed to engage is formed upon the upper end of the arm 28. At the rear of the said shoulder is a pocket 28^b. The said pocket is partly covered by the lip 28^c, which is constituted by a strip of metal that is fastened to the top of the arm 28 at the rear of the pocket and projects forward over the latter. The clearance between the front end of the lip and the shoulder is sufficient to permit the dog 27 to pass in and out beneath the lip by relative rearward and forward movement, and the depth of the pocket at the rear of the shoulder 28^a is sufficient to accommodate the dog.

As thus far referred to, the parts constitute a separate invention, and are not broadly claimed herein.

Figs. 1 and 2 show the parts combined and arranged as they are employed for pick-finding purposes for three-harness weaving. The dog 27 occupies a position in contact with the under side of the lip 28^c, and elevated above shoulder 28^a. This is its normal or starting position for three-harness work, and it is held in such position through the agency of a link 39 having its upper end connected by a pivot 39^a to the downwardly-extending finger 26^a of arm 26 and its lower portion slotted longitudinally at 39^b, and a screw-stud 39^c carried by an arm 37 fixed upon the cross-rod or shaft 21. The stem of the said screw-stud works in the slot 39^b, and normally engages with the wall at the upper

end of such slot so as to lift and support the link and arm 26, and keep the dog 27 pressed against the under side of the lip.

The operation, in general, of the pick-finder devices when arranged and combined as in Figs. 1 and 2, is fully explained in United States Letters Patent No. 1,040,547, granted Oct. 8, 1912, on my co-pending application filed June 10, 1908, Serial No. 501,316. It is sufficient to state herein that should the weft fail on the pick of the shuttle from the magazine side of the loom to the driving side thereof, or should the weft laid on such pick be excessively slack, so that the weft-fork 15 remains untilted when the lay beats up, the engagement of the actuator 18 with the tail of the said fork, and resulting advance of slide 16 and arm 26, will move dog 27 forward out from under the lip 28^c. Then, as the actuator moves rearward, the slide and arm will accompany it, and the dog having been raised slightly through the action of a spring (not shown) in connection with the devices (not shown) at the other side of the loom, the lifting force transmitted from such spring being sufficient to overcome the depressing force exerted by the spring 29, the rearward movement will place the dog above the lip 28^c. It being assumed that no weft is laid in position to act upon the weft-fork at the magazine-side of the loom by the pick to the latter side from the driving-side, which ordinarily will be the case after failure on the preceding pick as above recited, and that none is laid in position to act upon the weft-fork 15 by the ensuing pick from the magazine-side to the driving-side, the devices will act in regular predetermined manner. The result is that when the second advance of slide 16, which now is occasioned, carries the dog 27 forward from the lip 28^c, the arm 26, it having been relieved from the lifting effect of the spring at the other side of the loom, drops until dog 27 rests upon the forward portion of arm 28, and when the slide 16 next moves rearward the dog falls behind shoulder 28^a. In the next advance of the said slide, the dog 27 acts against the shoulder to move the arm 28 forward, rocking the tripping rockshaft 11 so as to trip the shipper-handle and also call the replenishing instrumentalities into action. If failure of the weft at a pick from the magazine-side of the loom to the driving-side should be due to breakage thereof outside the shuttle, leaving a trailing end which is not long enough to act to tilt the weft-fork 15 when the lay beats up with the shuttle in the shuttle-box at the latter side, so that the weft-fork devices act as described to produce the first advance of the dog and cause the latter to assume its secondary position, namely, on the top of the lip, and if in the flight of the shuttle through the next shed, from the

driving-side of the loom to the magazine-side, or in the return flight from the magazine-side to the driving-side through the succeeding shed, the trailing end should 5 catch in the shed and become woven in, the weft would thereafter act in usual manner to tilt the weft-forks alternately. Thereby the operation of the pick-finding devices would be interrupted, and the regular working 10 of the loom would be continued without suspension of the weaving action, or replenishment, the dog however remaining in its said secondary position. When this occurs, it is important that the dog should be restored 15 to its normal starting position promptly, in order that the pick-finder devices may secure correct results when subsequently called into action again. The same situation would present itself in case the 20 weft laid by the pick from the magazine-side to the driving-side should be too slack to tilt the fork at the latter side, but should act to tilt the fork at the magazine-side on the return pick to the latter side from the 25 driving-side.

Fig. 3 shows the pick-finder devices combined and arranged as they are employed for four-harness weaving. In this figure, link 39 and screw-stud 39^c are omitted, inasmuch as the dog is not under control of the 30 weft-fork at the magazine-side. The normal or starting position of the dog is upon the top of the lip. When the pick-finding sequence is begun, so as to cause the dog to be carried forward from the lip and permit 35 it to drop and pass rearward under the lip, and then such sequence is interrupted, as in either of the cases above referred to, leaving the dog in its secondary position beneath the 40 lip, the same necessity for replacement of the dog in its normal starting position exists as in the case already described with reference to Figs. 1 and 2.

The means illustrated in the drawings for 45 restoring the dog and lip to normal starting relation in case a sequence of beats that has been begun is interrupted, leaving the dog and lip in abnormal relation, comprises a reciprocating member which by engagement 50 with the dog when the latter has been allowed to remain in its secondary position returns it to the normal or starting position. In the illustrated embodiment of the invention this member is, for convenience, actuated 55 by means of the weft-hammer or goose-neck 18, the arrangement and timing of the latter being well suited to the requirements and consists, essentially, of a push-pin, *a*, which is connected to the head of the weft-hammer 60 so as to move forward and backward in unison therewith, and is arranged to engage with the arm 26 at one side of the pivotal axis of the latter. When such engagement takes place, the tendency is to 65 turn said arm around the said axis. For

the purpose of such engagement the arm 26 is shown formed with upper and lower wings *b*, *b'*, which are shown best by Figs. 4, 5 and 6. The push-pin is held in proper position for action in connection with one 70 or the other of such wings by being placed within one or the other of the holes *c*, *c'*, Figs. 7 and 8, which are provided in a stand *d*, and by means of such stand it is guided as it is reciprocated endwise. In Figs. 1 75 and 2 the normal or starting position of the dog being below the lip, the abnormal or secondary position is above the lip. Consequently, the push-pin is caused to occupy the upper hole, *c*, of the stand *d*, to act against 80 the upper wing of the arm 26, so as by pressing against the said upper wing to transfer the dog from the upper side of the lip to the lower side thereof. In Fig. 3, the normal or starting position of the dog being 85 above the lip, the abnormal or secondary position is below the same, and consequently the push-pin occupies the lower hole *c'*, of the guide-stand *d*, so that by pressing against the lower wing of the arm 26 the 90 said push-pin may operate to move the arm to transfer the dog from the lower side of the lip to the upper side thereof. The push-pin *a* is, for convenience, connected with the head of the weft-hammer by means of a 95 connector *e*, the latter consisting of an L-shaped piece, to one arm of which the push-pin is attached, the other arm thereof being engaged with the stem of a pivotal screw *f*, which is applied to the said head. To 100 provide for lengthwise adjustment of the push-pin, so as to enable its action upon the arm 26 to be varied as required, the push-pin is screw-threaded at the end thereof which is engaged with the connector. This 105 end is placed in a hole in the outstanding arm of the connector, and receives upon it at opposite sides of such arm nuts and washers *e'*, *e'*. By turning the nuts the desired adjustment may be effected. 110

In operation, each time the weft-hammer 18 beats forward it produces a forward stroke of the push-pin *a*. If weft-fork 15 is tilted by the weft, as ordinarily will be the case, so that the tail 15^a thereof is uplifted 115 and consequently missed by the shoulder 18^a of the weft-hammer, the slide 16 and arm 26 will remain at rest. As the push-pin completes its said stroke its forward end will encounter the wing *b*, or *b'*, with which it is 120 arranged to coact, in case the arm 26 and dog 27 occupy their secondary position, and will act to swing the arm so as to effect the transfer of the dog to the normal or starting position. In case the weft-fork remains 125 untilted because of weft-absence, or undue slackness of the weft, so that the shoulder of the weft-hammer engages the tail of the weft-fork and causes the slide 16 to advance, the arm 26 will also be advanced in unison 130

with the push-pin so that the latter will have no effect in transferring the dog. Consequently, the action of the dog and other parts will take place as heretofore, unmodified by the push-pin.

To facilitate the action in transferring the dog from one side of the lip to the other, the arm 26 is slotted longitudinally at 26°, Figs. 5 and 6, for the screw 23. The action of spring 29 normally holds the forward end-wall of the slot against the stem of such screw, but when the pressure of the push-pin takes effect against one of the wings, *b* or *b'* as the case may be, while dog 27 is still engaged with one side of lip 28° so as to oppose the tendency of arm 26 to turn upon screw 23 as a pivot, the said spring yields to permit the arm 26 to move forward relative to slide 16 until the dog has been carried free of the lip, which leaves the arm free to turn to the slight further extent required. As the pressure of the push-pin against the wing with which it is engaged is relieved, the arm 26 is drawn rearward again by the action of spring 29, carrying dog 27 back with it at the proper side of the lip 28°.

What is claimed is:—

1. The combination with a transmitting member, a dog, and a lip and a shoulder with which the dog coacts, such coaction involving a shift of the dog from one side of the lip to the other, and a weft-detector under control of which the interaction of dog, lip, and shoulder occurs, of means acting to restore the dog to the original side of the lip in case a sequence of beats that has been begun is interrupted.

2. The combination with a transmitting member, a dog, and a lip and a shoulder with which the dog coacts, such coaction involving a shift of the dog from one side of the lip to the other, and a weft-detector under control of which the interaction of dog, lip, and shoulder occurs, of a reciprocating member which restores the dog to the original side of the lip in case a sequence of beats that has been begun is interrupted.

3. The combination with a transmitting member, a dog, and a lip and a shoulder with which the dog coacts, such coaction involving a shift of the dog from one side of the lip to the other, a weft-fork under control of which the interaction of dog, lip, and shoulder occurs, and a weft-hammer, of means through which the weft-hammer restores the dog to the original side of the lip in case a sequence of beats due to engagement of the weft-hammer with the weft-fork is begun and left uncompleted.

4. The combination with a weft-detector, a dog operated under the control of the weft-detector, and a transmitting member having a shoulder adapted to be engaged by the dog and a lip which controls the action of

the dog, the operation of the parts involving a shift of the dog from one side of the lip to the other, of means for restoring the dog to the original side of the lip in case of uncompleted operation of the dog leaving it at the other side thereof. 70

5. The combination with a weft-detector, a transmitting member having a shoulder and a lip, and a dog to engage the said shoulder to move the said member, the said dog being operated under the control of the weft-detector, also governed in its action by the lip, and having a normal starting position at one side of the lip, of means to return the dog to the said side in case of uncompleted operation of the dog leaving it at the other side thereof. 75

6. The combination with a weft-detector, a movable carrier therefor, a dog movably mounted in connection with the said carrier, and a transmitting member having a shoulder to be engaged by the said dog in the movement of the carrier, and a lip at one side of which the dog is set for its starting position, of means to return the dog to the 80 said starting position in case uncompleted operation of the dog leaves it at the other side of the lip. 90

7. The combination with a weft-detector, a transmitting member having a shoulder and a lip, and a dog to engage the said shoulder to move the said member, operated under the control of the weft-detector, also governed in its action by the lip, and which is adapted to have at will a normal starting 95 position at either side of the lip according to the results to be attained in action, of means to return the dog to the selected normal position in case of uncompleted operation of the dog leaving it in a different position, 100 manually controlled to conform to the variation in the said starting position of the dog. 105

8. The combination with a transmitting member having a shoulder and lip, a weft-detector, a movable carrier therefor, and a dog to engage the said shoulder to move the said member, the said dog being governed as to its action by the said lip, movably connected to the said carrier, and adapted to be set at will in a starting position at either 110 side of the lip according to the results to be attained in action, of means through which the weft-hammer restores the dog to the selected side of the lip in case the sequence of beats of the dog is begun and left uncompleted, manually controlled to conform to the variation in the said starting position of the dog. 120

9. The combination with a transmitting member having a lip, a weft-detector, a movable carrier for said weft-detector, a weft-hammer, a dog pivoted upon the said carrier, governed as to its actuation of the said member by the said lip, and adapted to be set at will in a starting position at either 125 130

side of the lip, according to the results desired in operation, of replacing means operated by the weft-hammer, adjustable to act at either side of the pivot of the dog, as required to restore the dog to predetermined starting position.

10. The combination with a transmitting member, a dog, and a lip and a shoulder with which the dog coacts, such coaction including a shift of the dog from one side of the lip to the other, a weft-fork under control of which the interaction of dog, lip, and

shoulder takes place, and a weft-hammer, of a replacer moving in unison with the weft-hammer and by which the dog is restored to the original side of the lip in case a sequence of beats that has been begun is interrupted.

15 In testimony whereof I affix my signature in presence of two witnesses.
